UNITED STATES PATENT OFFICE

LAURENCE M. PERSONS, OF ST. LOUIS, MISSOURI, ASSIGNOR TO EMERSON ELECTRIC MANUFACTURING CO., OF ST. LOUIS, MISSOURI, A CORPORATION OF MISSOURI

CENTRIFUGAL CLUTCH FOR MOTORS

Application filed August 16, 1929. Serial No. 386,397.

My invention relates to a centrifugal clutch for use with electric motors. One object is the provision of such a clutch which shall be simple to manufacture, sturdy, and efficient 5 in operation. Another object is the provision of such a clutch which shall have a maximum clutching or clamping action. Other objects will appear from time to time in the course of the specification and claims.

10 I illustrate my invention more or less diagrammatically in the accompanying drawing, wherein—

Figure 1 is an axial section;

15 Figure 2 is a section on the line 2—2 of Figure 1;

Figure 3 is a section on the line 3—3 of Figure 1;

Figure 4 is a section on the line 4—4 of Figure 2; and

20 Figure 5 is a detail.

Referring to the drawing, A generally indicates a motor housing within which any suitable field structure A¹ is positioned.

B indicates a motor shaft the ends of which

25 may be supported in bearings as at B¹. Mounted about the shaft B is the sleeve B² which may be held against rotation in relation to the shaft as by the screw B³. Radially extending from the sleeve B² is the circum-

30 ferential flange B⁴ which is thickened at its outer edge as at B⁵. The inner face of said flange is inclined as at B⁶ and set therein is the frictional member B⁷ with its inclined exposed face B⁸. It will be understood that

35 the structure as a whole rotates in unison with the shaft B.

Mounted about the shaft B is the armature structure generally indicated as C which may include the inner sleeve C¹ and bearing portions

40 C² opposed to the external face of the shaft B and rotatable in relation thereto.

Secured to one end of the armature is the cruciform guiding element generally indicated as D. It is provided with the dia-

45 metrically opposed guiding arms D¹ D¹ and the intermediate arms D² D². These various arms are secured to the armature as by the screws D³ which pass through the bushings

50 D⁴. It will be understood that the member D is centrally apertured as at D⁵, the aperture

being of such size as to clear the shaft B and the sleeve B². The inner edge of the aperture D⁵ is inwardly offset as at D⁶.

Slidable along the guiding arms D¹ D¹ are the centrifugal weights generally indicated 55 as E, E. Each such weight includes a portion E¹, the portions E¹ of the two weights being connected by the springs E² E² which tend to draw the weights together and to move them toward the center of rotation of 60 the motor. The portion E¹ of each weight includes hook elements E³ E³ which, as shown in Figure 4, surround the edges of the guide arm D¹. As will be seen in Figure 4 the proportion of parts is such that a certain amount 65 of lateral play in relation to the guide arm D¹ is possible, permitting the weight a certain degree of movement in the general plane of the arm D¹. Extending radially outwardly from each member E¹ is the wedge portion 70 proper E⁴. As will be seen for example in Figure 1 this portion E⁴ conforms generally to the opposed wedging surface B⁸ of the frictional element B⁷.

It will be understood that when rotation of 75 the armature C is initiated, as the armature comes up to speed the cruciform member D will be rotated and a centrifugal movement will be imparted to the weights E which tends to separate them, against the resistance 80 of the springs E². As this centrifugal movement continues the wedge portions E⁴ of the weights engage the frictional element B⁷ and the result of the inclination of the opposed 85 surfaces is a wedging action which effects the clamping or clutch action which is desired.

The disposal of parts herein disclosed provides a compound multiplication of power to the clutch surfaces. In the first place, the angle of the opposed clutch faces of the 90 members E⁴ and B⁷ produces a multiplication or wedging action, in response to the centrifugal movement of the wedges against the frictional member. In the second place the drag on the weights which follows from 95 their impingement against and frictional contact with the member B⁷ causes an increased outward force by the angle which they take in relation to the supporting or guiding arms D¹. The slight lateral clear- 100

ance above mentioned permits the weights to tilt slightly in relation to their supports and this tilting action causes an additional compression or outward exertion of force against the frictional member B'. As the weights come into contact the resulting drag causes an increased outward thrust since the hook elements E³ do not constrain the weights E to strictly radial movement but permit them to take a slight angle to the radius.

I claim:

1. In a clutch structure adapted for use with a motor, a fixed clutch member and a centrifugal clutch member mounted for generally radial movement, the clutch members being provided with opposed wedging clutch surfaces the surfaces of each clutch member defining a single cone, and guiding means for the centrifugal member adapted to permit it to tilt somewhat in response to the drag caused by its contact with the fixed clutch member.
2. In a motor and clutch structure, a motor shaft, an armature rotatable about said shaft, and a clutch assembly adapted in response to the rotation of the armature to lock said shaft and armature against relative rotation, which includes a fixed clutch member, and a centrifugal clutch member mounted for generally radial movement, the clutch members being provided with opposed wedging clutch surfaces and means tending normally to move the centrifugal clutch member into inoperative position, and guide means for the movable clutch members adapted to permit said movable clutch members to cant or tilt slightly from a normally radial path in response to its engagement with the fixed clutch member.
3. In a motor and clutch structure, a motor shaft, an armature rotatable about said shaft, and a clutch assembly adapted, in response to rotation of the armature, to lock said shaft and armature against relative rotation, which includes a clutch member fixed in relation to the shaft, including a circumferentially frictional member having a wedging clutch surface, and a pair of centrifugal clutch members mounted on the armature, and means for guiding them for diametrically opposed and generally radial movement, said centrifugal members being provided with wedge faces opposed to the wedge face of the frictional member, the centrifugal members being mounted to permit them to tilt slightly laterally in response to their contact with the frictional member.
4. In a motor and clutch structure, a motor shaft, an armature freely rotatable thereon, a clutch member fixed to the motor shaft and having a frictional clutch surface arranged in opposition to an end wall of the armature, guide means carried by the armature and including substantially radially

disposed guiding surfaces, certain of which surfaces are disposed in planes substantially perpendicular to the axis of rotation of the armature and certain of which surfaces are disposed in planes substantially parallel to said axis, and movable clutch members positioned on said guide means and operable in response to centrifugal force in the armature when rotated to move radially into clutching engagement with the first mentioned clutch member, said movable clutch members including portions embracing the guiding surfaces of the guide members and having surfaces parallel with the cooperative guiding surfaces of said guide means, said portions being dimensioned to maintain the cooperative guiding surfaces of the guide member and clutch members that are disposed in planes substantially perpendicular to the axis of rotation and to permit a substantial amount of lost motion between the cooperative guiding surfaces that are disposed in planes substantially parallel to the axis of rotation.

5. In a centrifugal clutch, a shaft mounted for rotation, a clutch member fixed thereto, and including a conical clutch surface, a member mounted on the shaft for free rotation, movable clutch members carried by said members and provided with inclined faces cooperatively disposed with reference to said conical clutch surface, guide means engaged by the movable clutch members and by which said members are directed into operative engagement with the conical clutch surface under the influence of centrifugal force, said movable clutch member and guide means being relatively dimensioned to permit slight canting of said movable clutch members from engagement with the conical clutch surface whereby to increase the friction contact between said clutch members.

6. In a clutch structure adapted for use with a motor, a fixed clutch member and a centrifugal clutch member mounted for generally radial movement, the clutch members being provided with opposed wedging clutch surfaces, and guiding means for the centrifugal member adapted to permit it to tilt somewhat in response to the drag caused by its contact with the fixed clutch member, the guiding means for the centrifugal member including a radial guide, there being sufficient clearance between guide and member to permit the member to tilt laterally somewhat in the plane of the guide.

7. In a motor and clutch structure, a motor shaft, an armature freely rotatable thereon, a clutch member fixed to the motor shaft, said clutch member having a frictional concave clutch surface arranged in opposition to an end wall of the armature, such clutch surface defining a cone, guide means secured directly to an end of the armature, and movable clutch members positioned on said guide

means and operable in response to centrifugal force in the armature when rotated, to move radially into clutching engagement with the first mentioned clutch member, said clutch members being formed with clutch surfaces adapted, when in clutching position, to define a convex cone.

8. In a motor and clutch structure, a motor shaft, an armature freely rotatable thereon, a clutch member fixed to the motor shaft, said clutch member having a frictional concave clutch surface arranged in opposition to an end wall of the armature, such clutch surface defining a cone, guide means secured directly to an end of the armature, and movable clutch members positioned on said guide means and operable in response to centrifugal force in the armature when rotated, to move radially into clutching engagement with the first mentioned clutch member, said clutch members being formed with clutch surfaces adapted, when in clutching position, to define a convex cone, there being sufficient clearance between the guide means and the movable clutch members to permit said members to tilt laterally somewhat in the plane of the guide means.

Signed at St. Louis, and State of Missouri,
this 1st day of August, 1929.
